Primary Examiner—Carmen H. Vales-Lado
Attorney, Agent, or Firm—Ryan Kromholz & Manion, S.C.**[57]****CLAIM**

The ornamental design of fireplace entertainment center, as shown and described.

DESCRIPTION

FIG. 1 is a right side perspective view of the fireplace entertainment center showing my new design, the opposite side being a mirror image thereof;

FIG. 2 is a perspective view with the left side compartment in open position and some shelves in extended position; and, FIG. 3 is a perspective view with all the compartments in open position, the other side being a mirror image thereof. The rear and bottom of the center not shown in the drawing or described in the specification form no part of the claimed design.
